UNITED STATES PATENT OFFICE.

JOSEPH P. BAUMGARTNER, OF PHILADELPHIA, PENNSYLVANIA.

GARTER BUTTON AND GARTER FASTENING.

Application filed January 19, 1925. Serial No. 3,263.

My invention relates to men's garters and particularly to the fastening between the garter sections which support the loop leading down to the stocking and to the mounting of a button by which connection and disconnection about the leg of the wearer are secured.

One purpose of my invention is to mount a connecting and disconnecting button which passes through the fabric of a garter elastic upon a support lying between the folds of the elastic, transmitting the strain upon the bend of this fold and protecting the opening in the elastic by a flange upon the button.

15 A further purpose is to take the strain of a fastening button passing through the elastic upon the loop of the elastic so as not to disturb the fabric where it is apertured for the button.

20 A further purpose is to cut the elastic without severing it, to fold it until the parts of the cut are closed, to return the end of the fabric against this joint to give a diagonal relation at the meeting ends, to secure 25 the parts together in this position and to reinforce this joint by the depending strap for stocking attachment.

Further purposes will appear in the specification and in the claims.

30 I have preferred to illustrate my invention by a single form only, selecting a form which is practical and has proved to be efficient and reliable and which at the same time well illustrates the principles of my invention.

Figure 1 is a fragmentary side elevation of the end of the garter carrying the stocking loop.

Figure 2 is a section of Figure 1 taken 40 upon line 2—2.

Figure 3 is a perspective of the button seen in Figure 2.

Figure 4 is a reduced side elevation of the elastic fabric shown in Figure 1, marked for 45 cutting.

Figure 5 is a side elevation showing the structure of Figure 4 cut.

Figure 6 is a side elevation of the structure of Figure 5 folded to position and 50 roughly secured together.

Figure 7 is a side elevation of the joint shown in Figure 6 after the stocking-sup-

porting strap has been attached but before the button is in place.

Figure 8 is a section of Figure 7 taken 55 upon the line 8—8.

In the drawings similar numerals indicate like parts.

The fabric 10, forming the end of the garter which carries the depending loop for 60 stocking support, is shown in Figures 1 and 7 in final position with the two parts or branches 11 and 12 forming the usual angle to each other so as to avoid direct constriction of the leg of the wearer. 65

In the form shown the fabric is integral and is shown in its initial condition in Figure 4, where the straight fabric length is marked for cutting at 13, 14 to form a V opening 15 and a diagonal end 16. When 70 folded back this end may correspond with the edge 17 of the V. The fabric is turned or bent in its own planes until the edges 16 and 17 meet the edge 18 as seen best in Figure 6. These edges are then fastened 75 together, preferably by metal fastenings 19. This gives both a temporary hold and a means of stiffening and strengthening the joint.

The loop 20 is folded at the middle at 21 80 and the ends are folded back upon each other as at 22 and 23 so that each of the depending sides or parts of the loop is shown as double at 24 and 25. This reversely-turned doubled loop is placed over the joint 85 seen in Figure 6 and the parts are stitched to position as at 26 seen in Figure 1. This additionally stiffens the joint by the fabric facing and by any desired amount of stitching. 90 The loop is shown in Figure 1 as supporting the stocking fastening device 27.

The loop 28, formed by folding back the fabric in Figure 5, is utilized for the double purpose of giving additional strength at this point and so that the fabric at the end 95 of the loop will take the strain of the fabric-piercing button 29.

The button has an enlarged shank 31 between the plate 30 and the flange 32 so that 100 the elastic fabric may be apertured to correspond substantially to the size of this shank and may be placed by stretching to position over the flange 32. It will contract about the shank resting easily about it at the same

time that the edge 33 of the plate engages with the inner side of the bend in the loop and the button flange holds together the loose fabric edges about the aperture and covers them.

The outer part of the button is formed with a neck 34 and head 35 for attachment of a metal loop (not shown) secured to the free end of the garter.

10 The button with its loop support lies very close to the joint and is given additional rigidity by it. The joint is firmer and stronger by reason of the double fastenings provided.

15 It will be obvious that variations and changes will occur to those skilled in the art, utilizing the advantages of my invention without closely following the structure; and it is my purpose therefore to include

20 herein all such as fall within the reasonable spirit and scope of my invention.

Having thus described my invention, what I claim as new and desire to secure by Letters Patent is:—

25 1. In a garter, a stocking-supporting strap, an elastic fabric secured thereto and folded reversely to form a loop adjacent to the outer end of the fabric, a plate within

the loop, a button riveted to the plate, passing through an aperture in one side of the 30 fabric and enlarged with respect to the rivet where it passes through the fabric, a flange upon the button holding the fabric close to the plate about the enlargement, a neck upon the button outside of the flange and a head 35 upon the outer end of the button adjoining the neck.

2. In a garter, a fabric end slitted transversely part way through to allow bending in the same plane so that the lengths of the 40 adjoining sections are at an angle, diagonally cut at the end and folded back laterally to bring the end into agreement with the edge of the slit, strap fastenings across the joint thus formed and a stocking-supporting loop enclosing the joint and stitched to it.

3. In a garter, an integral garter end, bent in the same plane to bring the lengths of adjoining sections at an angle to each other and 50 folded laterally to bring one end of the fabric into line with the joint a fastening to hold the joint thus formed and a stocking-supporting strap about the joint and secured to it to stiffen the joint.

JOSEPH P. BAUMGARTNER.
